JAMES MCPHAIL, OF CHARLES CITY, IOWA.

Letters Patent No. 96,941, dated November 16, 1869.

IMPROVEMENT IN BAG-HOLDERS.

The Schedule referred to in these Letters Patent and making part of the same

To all whom it may concern:

Be it known that I, JAMES MCPHAIL, of Charles City, in the county of Floyd, and in the State of Iowa, have invented certain new and useful Improvements in Adjustable Bag-Holders; and do hereby declare that the following is a full, clear, and exact description thereof, reference being had to the accompanying drawings, and to the letters of reference marked thereon, making a part of this specification.

The nature of my invention consists in the construction and arrangement of an adjustable bag-holder, as will be hereinafter fully set forth.

In order to enable others skilled in the art to which my invention appertains, to make and use the same, I will now proceed to describe its construction and operation, referring to the annexed drawings, in which—

Figure 1 is a side view, and

Figure 2 is a rear elevation of my invention.

A represents the bed-piece, on one side of which is the standard B.

This standard is provided with a dovetailed vertical groove on the rear side, to allow the sliding bar C to move freely up and down in the same.

The edges of the sliding bar C are bevelled so as to fit in the dovetailed groove above mentioned, and one of its edges is provided with a series of notches, as seen in fig. 2, in which the end of an arm, D, fits.

Said arm being pivoted on the upper end of the standard B, allows the sliding bar C to be held at any height desired.

At the upper end of the sliding bar C, is a horizontal cross-bar, E, of suitable dimensions, to which the jaws G G are pivoted, in the following manner:

The jaws G G are of the shape shown in the drawings, or may be of any other suitable shape, so as to form together, so to say, the one-half of a hopper.

Each jaw is provided with a rod, a, running at or near its edge, then bent toward the rear, and passes through a box, b, at the end of the bar E, thus hinging or pivoting the jaws to said bar.

The rods a a are then bent along the rear side of the bar E, and are, at their ends, provided with pivoted levers d d.

These two levers are, at their lower ends, connected by a rod, o, which passes downward, and is attached to a lever, H, pivoted at a suitable point on the rear side of the sliding bar C, said lever being held at any desired position by a ratchet-bar, I, which is also secured to said sliding bar.

The rods a a are provided with suitable hooks, e e, on which the bag or sack is suspended.

It will readily be seen, that by this arrangement of the adjustable jaws G G, the holder can be easily adapted to any-sized bag. The adjustment of the sliding bar C allows it to be used at any height desired.

Having thus fully described my invention, What I claim as new, and desire to secure by Letters Patent, is—

1. The combination and arrangement of the bed-piece A, grooved standard B; notched sliding bar C, and arm D, all substantially as and for the purposes herein set forth.

2. The arrangement of the rods a a, levers d d, rod o, lever H, and ratchet-bar I, all substantially as and for the purposes herein set forth.

3. The combination and arrangement of the bed-piece A, grooved standard B, sliding bar C, arm D, jaws G G, rods a a, hooks e e, levers d d, rod o, lever H, and ratchet-bar I, all constructed as described, and operating substantially as and for the purposes herein set forth.

In testimony that I claim the foregoing, I have hereunto set my hand, this 18th day of September, 1869.

JAMES MCPHAIL.
